UNITED STATES PATENT OFFICE.

LEWIS REASER, OF READING, PENNSYLVANIA.

HANDLE FOR SHEET-METAL VESSELS.

SPECIFICATION forming part of Letters Patent No. 718,656, dated January 20, 1903.

Application filed March 20, 1902. Serial No. 99,112. (No model.)

To all whom it may concern:

Be it known that I, LEWIS REASER, a citizen of the United States, residing in the city of Reading, county of Berks, State of Pennsylvania, have invented certain new and useful Improvements in Handles for Sheet-Metal Vessels, of which the following is a specification.

My invention relates to an improved handle mechanism adapted particularly for use in connection with sheet-metal kitchen utensils and the like.

The invention is fully described in connection with the accompanying drawings, and the novel features are specifically pointed out in the claims.

Figure 1 is a face view of my improved handle device as applied to a sheet-metal utensil. Fig. 2 is a cross-sectional view taken on the line $x-x$ of Fig. 1. Figs. 3 and 4 are separate views of the stamped blanks for the sheet-metal handle-bracket and handle, respectively.

A represents in end elevation the body of a washboiler, for instance, having a central vertical seam a , as usual, and B represents the handle ordinarily applied thereto at each end near the top edge of the vessel. In order to provide for properly distributing the strain brought upon the body of the vessel by supporting its loaded weight by means of these handles and at the same time provide a neat, inexpensive, and substantial handle device, I form a handle-bracket C out of sheet metal stamped to shape by means of suitable dies, as shown in Fig. 3. This stamped blank for the handle-bracket is T-shaped, the stem portion 2 being adapted to extend downward over the seam a of the vessel A, while the head or cross-plate 3 extends parallel with the top edge a' of the vessel and is of greater width than the length of the handle B. The latter is secured between ears 4 4, which are preferably formed in the plate C, as shown, by cutting the central portion of said cross-plate along the lines 5 5 in the process of stamping, thus leaving the ear portions 4 4 attached to the bracket C only at 6 6, adjacent to the ends of the cross-plate 3, and permitting them to be turned bent outward at right angles to said plate and paral-

lel with each other at a distance apart adapted to permit the introduction of the handle B between them. To give stiffness to the sheet-metal structure and at the same time improve its appearance, I press into the metal, in the process of stamping, suitable strengthening-ribs 7 and 8 and a beaded edge 9, and I also provide rivet perforations 10 to secure the bracket to the vessel A.

The handle B may be of wood, as usual, secured between the ears 4 4 in any usual manner; but I prefer to employ a sheet-metal handle of special construction, at the same time adapting the ears 4 4 to receive this preferred form of handle. In Fig. 4 is shown the sheet-metal blank B', from which this handle is formed, consisting merely of a rectangular plate preferably provided with perforations 11 and having end extensions 12 12, of reduced width, adapted when the blank is bent up into cylindrical form to serve as a handle to enter the curved perforations 13 13, provided in the projected ends of the ears 4 4 of the bracket C. These extensions 12 12 are shown notched at 14 14, so that after the said projections of the formed-up handle have been entered in the curved perforations 13 13 the handle may be slightly turned, so as to lock it to the ears prior to flanging over the said projections against the outer faces of said ears to rigidly connect the handle thereto, which operation completes the construction.

It will be readily seen that the strain upon the handles is by means of my improved construction so distributed over the surface of the vessel A as to avoid undue strain upon a small portion of the latter, such as ordinarily occurs, while at the same time the general construction of the vessel is strengthened and its appearance improved.

What I claim is—

1. A handle-bracket of sheet metal stamped to approximately T shape and having the central portion of the cross-plate or head thereof partially severed to form integral separated handle-ears, said ears being bent into parallel position approximately at right angles to the plate.

2. A stamped sheet-metal blank for a handle-bracket of approximately T shape having similar alined and partially-severed ear por-

tions 4 4 formed within the borders of the cross-plate thereof and suitably ribbed and perforated substantially as and for the purpose set forth.

5 3. The combination with a handle-bracket having parallel ears each provided with a semicircular perforation, of a hollow cylindrical handle formed of a single piece of sheet metal having projecting end portions adapted

to engage said perforations substantially as is set forth.

In testimony whereof I affix my signature in the presence of two witnesses.

LEWIS REASER.
